UNITED STATES PATENT OFFICE.

FREDERICK W. HEDGELAND, OF CHICAGO, ILLINOIS.

ACETYLENE-GAS-GENERATING LAMP.

SPECIFICATION forming part of Letters Patent No. 644,768, dated March 6, 1900.

Application filed November 6, 1899. Serial No. 735,885. (No model.)

To all whom it may concern:

Be it known that I, FREDERICK W. HEDGELAND, a citizen of the United States, residing in Chicago, in the county of Cook and State 5 of Illinois, have invented a new and useful Improvement in Acetylene-Lamps, of which the following is a specification.

This invention relates to improvements in self-regulating acetylene-lamps.

10 My object in the invention is to reduce such lamps to a very compact and small form without detracting from the efficiency of the lamp or its ability to automatically regulate the generation of the gas.

15 The details of the invention are fully set forth in the description which I give below and are also illustrated in the accompanying drawings, in which latter—

Figure 1 is a front elevation of my improved 20 lamp with the hood removed. Fig. 2 is a vertical section of the carbide and water chamber, and Fig. 3 is a central vertical section at right angles to the plane of Fig. 2. Fig. 4 is a top view of the carbide-holding or generating chamber with the cover removed. Fig. 25 5 is a partial detail section.

In said drawings, A represents the reflector or hood of the lamp, and B the ventilator therefor. The gas-burner C enters the hood 30

35 through a bottom opening, as shown at Fig. 3. The hood is provided with a backwardly-projecting stud A', which enters a socket A' and is attached thereto by a screw, as shown. The burner passes centrally through a portion 35 of a vertical air tube or passage D, which is preferably open at its bottom and also perforated in front near the bottom, as shown at D', and the opening into the hood is large enough to admit air all around the burner.

40 The tube D surrounds the opening and prevents too-direct access to the flame by outside air-currents. The interior of the hood serves as a reflector, and it may be made in the form shown, which is a well-known form now extensively used.

The carbide and water holding parts of the lamp are made in the form of short cylinders E and F, preferably of the same size and general contour. These cylinders are arranged 50 close together and parallel immediately behind the hood, and the socket A' is attached

to one of them. The cylinder E is the carbide-holder, and in order that it may be conveniently charged and emptied I make the top E' removable. To render the joint between the top and the cylinder tight, so that the gas cannot escape, a suitable packing E² is interposed between them. The cover is threaded to the cylinder and permits the necessary compression of this packing.

60 The cylinder F contains the water, and it is preferably divided by a horizontal partition F' into two chambers, one of which is the water-reservoir F² and the other the equalizing-chamber F³, the latter being below the former. The water-reservoir is charged through the nozzle F⁴, normally closed by the screw-stopper F⁵. A vent F⁶ in this stopper may be employed for safety to give escape to any gas which may find its way up through 70 the water in the reservoir. With my improved means of self-regulation it very rarely occurs, however, that the pressure becomes so excessive as to force the gas into the reservoir. The water is admitted from the reservoir to the equalizing-chamber through a vertical passage F⁷, controlled from the outside of the lamp by the valve F⁸, threaded in the outer wall of the reservoir.

75 The water is admitted to the side of the body of carbide from the equalizing-chamber through a horizontal passage G, formed by a cylinder threaded to the wall of the carbide-chamber and attached to a boss G', soldered or otherwise secured upon the wall of cylinder F by a nut G², threaded on the cylinder and having an inward flange or shoulder which confines it on the stud. The cylinder G may enter the carbide-chamber for a distance, as shown, if desired, and this end is covered or 90 protected by a screen G³, held in place by a surrounding ring-nut G⁴. It is not necessary that the cylinder should thus pass entirely through the wall of the carbide-chamber, it only being requisite that it deliver the water 95 to the carbide above the bottom of the carbide-chamber. The water enters passage G at an opening G⁵, located in the stud G' and just below the partition F'.

100 The gas as it is generated rises in the carbide-chamber and passes through a fine screen E³, consisting, preferably, of two plates of

perforated metal with a sheet of linen between them and secured in the inner depending flange E^4 of the cap E' . Between the inner flange E^4 and the outer flange of the cap a gas-
 5 passage E^6 is formed, and the gas rising through the screen moves into this passage through a connecting space or duct E^7 . A pipe H leads from the passage E^6 downward and is connected with the burner by a branch
 10 H' . It may also extend down to within a short distance of the bottom of the lamp, as shown by the broken lines in Fig. 1, the object in so extending it being to enable the user to run a wire clear through the pipe, and thus clean
 15 it out perfectly and easily. This pipe H is preferably located inside the chamber. A second vertical pipe J leads from passage E^6 down to the horizontal passage G and opens into the latter at its top, as plainly seen at
 20 Fig. 2, and permits the gas when the pressure becomes excessive to enter the horizontal passage G and drive the water back therefrom into the equalizing-chamber. As soon, however, after any such operation as the pressure
 25 of the gas is reduced so that a further supply is needed the pressure of the water in the tank acting upon the water in the equalizing-chamber causes the latter to again flow into the passage G and into contact with the
 30 carbid. While the lamp is in use these operations are continually recurring, and the generation is so quickly and perfectly controlled that a continuous bright and even light is obtained. To start the lamp, the valve F^8
 35 is opened, and as soon as the gas begins to issue a match is applied to the burner. To stop the lamp, the valve is closed. The pipe J can be cleaned readily by a wire and may be located inside the cylinder E , if preferred.
 40 The two cylinders E and F are held together by the cylinder G and the nut G^2 , and the union may be tightened by turning that nut upon the cylinder. When thus drawn together, the
 45 socket A^2 , which is attached to one of the cylinders and is hollowed out to fit the exterior of the other, prevents any relative motion by either cylinder.

The boss E^8 upon the cap E' is not a necessary feature and is employed simply to make
 50 the tops of the two cylinders look alike.

It will be noticed that my improved lamp is very simple and easy to manufacture and easy to clean, all parts being readily accessible, especially when the cylinders are detached from each other, as they may readily be by unscrewing the nut G^2 .

I claim—

1. In an acetylene-lamp, the combination of two companion cylinders arranged side by side, one containing the carbid, and the other the water-reservoir and equalizing-chamber, said equalizing-chamber being in communication with the carbid by a water-passage, and a gas-passage connecting said water-passage with the upper part of the carbid-cylinder, substantially as specified.

2. The self-generating acetylene-lamp, consisting of a burner, two separated companion cylinders, one for the carbid and the other for the water, a horizontal pipe forming the only communication between the cylinders and admitting water from the water-cylinder to the carbid-cylinder, a gas-passage conducting gas from above the carbid to said pipe, and means for controlling the admission of water when the lamp is not in use, substantially as specified.

3. The self-generating acetylene-lamp, consisting of a burner, two separated companion cylinders, one for the water and the other for the carbid, a cross-passage between the cylinders admitting water from one cylinder to the other, a gas-passage conducting the supply of gas whereby the generation is regulated to said cross-passage, and means in the water-cylinder for preventing access by the water to the carbid when the lamp is not in use.

4. The self-generating acetylene-lamp consisting of two separated companion cylinders, one containing the carbid, and the other the water, the latter being divided into a water-reservoir above and an equalizing-chamber below, a valved water-passage between said chamber and said reservoir, and a horizontal cylinder forming a water-passage between the equalizing-chamber and the carbid-cylinder and to which gas from above the body of carbid is admitted, said last-mentioned cylinder serving as a means of coupling the companion cylinders together, substantially as specified.

5. The self-generating acetylene-lamp consisting of two separated companion cylinders, one containing the carbid, and the other the water, the latter being divided into a water-reservoir above and an equalizing-chamber below, a valved water-passage between said chamber and said reservoir, and a horizontal cylinder forming a water-passage between the equalizing-chamber and the carbid-cylinder and to which gas from above the body of carbid is admitted, said last-mentioned cylinder being fixed to one of the companion cylinders and held to the other by a swiveled nut, substantially as specified.

6. In an acetylene-lamp, a carbid-cylinder having a removable top, a water-cylinder having a removable cap and containing a reservoir and an equalizing-chamber below the reservoir, a connecting-passage G fixedly attached to one cylinder and through which water flows from the equalizing-chamber to the carbid, a nut swiveled to the other cylinder and engaging the outside of said passage, a burner, a tube surrounding the burner and admitting air along the same, a hood having a rear projection and a socket between the cylinders and receiving said projection, substantially as specified.

7. The self-generating acetylene-lamp, consisting of twin cylinders E and F , arranged side by side, one containing the water and

the other the carbid, a burner communicating with the carbid-cylinder, and located centrally between and in front of the cylinders, a hood for said burner, a water-passage connecting the cylinders and permitting the water to feed to the carbid-cylinder and to which passage the gas has access, so that its

pressure may regulate the flow of the water, and means for shutting off the water from the carbid, substantially as specified.
